UNITED STATES PATENT OFFICE.

CHARLES EDWARD HAVILAND, OF LIMOGES, FRANCE.

DESIGN FOR A DISH.

SPECIFICATION forming part of Design No. 23,113, dated March 13, 1894.

Application filed February 15, 1894. Serial No. 500,311. Term of patent 14 years.

To all whom it may concern:

Be it known that I, CHARLES EDWARD HAVILAND, a citizen of the United States, residing at the city of Limoges, in the Republic of France, have invented and produced a new and original Design for a Dish and other Articles, of which the following is a specification, reference being had to the accompanying drawings, forming part thereof, and in

o which—

Figure 1 is a top view of a dish bearing my design, and Fig. 2 is a section of same on the dotted line 2—2 of Fig. 1.

The leading features of my design consist in the ornamental form and configuration of the rim of the dish, substantially as shown in the drawings.

In the drawings A designates the dish, and B the rim thereof, the ends of the dish being o provided with the depressions C and grooves D leading thereto. The outer edge or border of the rim B is divided by the curved in-

dentations E into sections F whose edges have scallops a separated by raised portions b, which render the scallops a observable 25 whether the dish is looked upon from above, as shown in Fig. 1 or at its side or edge, as shown in Fig. 2. At the points where the rim B is provided with the curved indentations E, there are, in relief, upon said rim the ornate scroll figures G. At the opposite ends of the dish, the rim B bears the ornamental scroll figures H in relief.

What I claim is—

The design for a dish and other articles, 35 substantially as shown and described.

Signed at the city of Limoges, in the Republic of France, this 10th day of January, 1894.

CHARLES EDWARD HAVILAND.
